UNITED STATES PATENT OFFICE

SAMUEL SCHERR, OF BALTIMORE, MARYLAND, ASSIGNOR OF ONE-HALF TO
H. MERRYMAN TIRALLA, OF BALTIMORE, MARYLAND

DESIGN FOR A CAKE

Application filed October 28, 1932. Serial No. 45,603. Term of patent 14 years.

To all whom it may concern:

Be it known that I, SAMUEL SCHERR, a citizen of the United States, residing at Baltimore, in the State of Maryland, have invented a new, original, and ornamental Design for Cakes, of which the following is a specification, reference being had to the accompanying drawing, forming part thereof.

The figure is a perspective view of a cake showing my new design.

The essential features of my design consist in a cake having four distinctive layers and embodying a bottom layer of cake, an intermediate layer of icing thereon, a frustro-conical layer of cake of smaller base than the lower layer of cake and disposed upon the intermediate layer of icing, and a top layer of icing.

I claim:

The ornamental design for a cake, as shown and described.

SAMUEL SCHERR.
